ATTOGNEYS'

UNITED STATES PATENT OFFICE.

TRION HORACE BAKER, OF LEICESTER, ENGLAND.

CORSET.

SPECIFICATION forming part of Letters Patent No. 767,030, dated August 9, 1904.

Application filed January 28, 1904. Serial No. 191,027. (No model.)

To all whom it may concern:

Be it known that I, TRION HORACE BAKER, a subject of the King of Great Britain, residing at Belvoir street, Leicester, in the county 5 of Leicester, England, have invented certain new and useful Improvements in or Relating to Corsets, of which the following is a specification.

This invention relates to corsets and the like 10 constructed in two or more sections.

Corsets when new are frequently left loosely laced at the back sections until they have conformed to the shape of the wearer's waist, and the loose lacing has the effect of leaving an 15 opening or openings from top to bottom of the corset, through which the cold passes, thereby often resulting in discomfort to the wearer. An obvious protective is generally adopted by the wearer temporarily placing over the said 20 opening a loose piece of fabric to protect the same. To overcome the disadvantage above named, the adjacent edges of each section of the corset are preferably formed in such a manner that they may be pulled apart a pre- 25 determined distance without breaking the continuity of covering-surface at that part or causing an opening between the sections such as hereinbefore referred to.

The invention consists, essentially, in forming 30 the aforesaid adjacent edges of each section with a series of tongues or the like having a series of openings between the tongues on the edge of one section of the corset being arranged opposite to and adapted to be in- 35 serted within the spaces in the opposing edge of the adjacent section of the corset.

In order that the invention may be fully understood, reference is had to the accompanying drawings, in which—

40 Figure 1 represents an inside view of a two-section corset constructed according to this invention. Fig. 2 is a section on line *a b* of Fig. 1, and Fig. 3 a broken view showing the two sections of the corset separated.

45 Like numerals refer to similar parts throughout the drawings.

The adjacent edges 3 3 where the two sections 2 2 of the corset are connected together at the back are formed with in process of 50 manufacture or have attached thereto a series

of projecting tongues 4 or equivalents of any suitable material having spaces 5 between. The two sets of tongues 4 4—one on each said edge 3—are so arranged as to engage in the said spaces 5 5 in the opposing edges of such 55 sections. The edges 3 3 may be connected together in any suitable manner and, as shown, may be laced, in which case the extremity or tip and the root of each tongue 4 are preferably provided with lace-holes 6, through which 60 the lace 7 passes. Lace-holes 6^a are also formed in the body part of the two sections of the corset opposite each space 5 and at a minimum distance from the edge 3 equal to the length of the tongues, so that upon the 65 two sections of the corset being drawn together by the aforesaid lace 7 the tendency of the tongues to ruck up and cause discomfort is prevented thereby.

It will be obvious that corsets constructed 70 according to this invention may have their two or more sections drawn apart a certain distance, depending upon the length of the tongues 4, without in any way breaking the continuity of covering-surface at the back of 75 the corset. It will also be clear that upon the said sections of the corset being drawn together again by the aid of laces 7 or the like the said tongues 4 are prevented from sticking up and causing discomfort by the fact of 80 the said laces passing through an eyelet in the tip and root of each tongue and in the body part of the corset-section, as aforesaid.

What I claim, then, is—

1. In a corset formed in sections, a series 85 of tongues formed on the adjacent edges of the sections having spaces therebetween, each tongue having eyelet-holes at the end and base thereof; and a lace passing through said holes and through holes formed in the body 90 of the corset opposite each of the said spaces, substantially as described.

2. A corset formed in sections, the meeting edges of which are provided with eyelet-holes and a lace passing through such holes and a 95 series of tongues with spaces therebetween the free ends of the tongues on one section passing into the spaces between the tongues on the opposite section and beyond the rear edge of the spaces so as to cover the gap 100

which would otherwise be left between the two meeting edges of the corset when the latter is loosely laced.

3. In a corset formed in sections the combination with the adjacent edges of such sections of a series of tongues having spaces between, each tongue having eyelet-holes, of a lace passing through said holes and through other holes formed in the body of the corset

opposite each of the said spaces substantially to as described.

In testimony whereof I affix my signature in presence of two witnesses.

TRION HORACE BAKER.
